UNITED STATES PATENT OFFICE.

CLARENCE R. SMITH, OF WINTHROP, MASSACHUSETTS.

PROCESS FOR PRODUCING A COUNTER, OVERLAY OR UNDERLAY.

Application filed January 29, 1924. Serial No. 689,376.

To all whom it may concern:

Be it known that I, CLARENCE R. SMITH, a citizen of the United States, and a resident of Winthrop, in the county of Suffolk 5 and Commonwealth of Massachusetts, have invented and discovered a new and useful Process for Producing a Counter, Overlay or Underlay, of which the following is a full and exact specification.

10 This invention relates to presses for printing from intaglio plates and dies, and it has for its object the effecting of an improved process for the production of a counter, overlay or underlay by means of which the 15 pressure of the impression member of the press is concentrated over the engraved or embossed lines of the plate into order to do better work.

Previous to my invention such counters 20 were produced by drawing a knife-tip along through the fiber-board close to the lines and then digging up to a suitable depth the portions of the fibre-board outside such cuttings.

In my new process I accomplish the result 25 in two ways, the first consisting in compressing to a predetermined level the portions of the fibre-board or other yielding material which are outside of the lines, and my second method consisting in punching 30 closely disposed lines of holes adjacent the printed lines, and then tearing up the portions of the material thus separated from the printed lines.

In the drawings forming part of this specification, Fig. 1 is an edge view of a press-table having thereon a counter, overlay or underlay produced by the preferred form of my process. Fig. 2 is a similar view of the production of another form of my process. Fig. 3 is a face view of a counter produced by either process. Fig. 4 is a partially 40 sectional view of a tool employed. Fig. 5 shows another tool. Fig. 6 shows another tool. Fig. 7 is a perspective view of a machine used in the process.

The reference numeral 1 designates the table of a well known form of intaglio press having dovetail ways 2 for receiving the lateral edges of a metal plate or slider 3 upon 50 which is cemented a sheet of heavy fiber-board or other suitable material 4. Upon the exposed surfaces of this yielding material 4, in one form of my process, is pasted a sheet of cardboard 4', and upon this is 55 produced the printed or embossed matter;

this being done in the usual manner while the plate and yielding material are in place upon the table 1.

The slider 3 is then removed from the press and laid upon the table 5 of a machine 60 much like a sewing machine, but one having a small punch, as 6 in Fig. 4, substituted for the needle. The end of this punch 6 is adjusted to reach through the cardboard 4' if used and slightly into the board 4; and, the machine being set into rapid motion to cause the punch to be correspondingly reciprocated, the slider 3 is carefully guided about upon the table 5 to cause the punch to form continuous lines of perforations close to but 65 outside of the printed or embossed lines on the cardboard 4'.

The sections of the cardboard outside of the lines severed by the perforations are then 70 detached from the board 4, leaving the sections bearing the printed lines elevated the thickness of the cardboard above the board 4. In case the sheet of yielding material 4 is 75 sufficiently light in color, the cardboard 4' may be dispensed with and the printing or embossing applied directly to its surface. Otherwise, the process remains as above described.

Where the blank spaces are large, as between the printed matter and the upper 80 corners illustrated in Fig. 3, the fine punch 6 is removed from the plunger 7 and a broader one 8 substituted therefor. Then, the plunger 7 being adjusted to descend 85 slightly farther than before, the slider 3 and its attached fibre-board 4 is moved about beneath the rapidly reciprocating tool 9 until the latter has beaten and compressed sufficient of the fibre-board, as at 13, to 90 render the printed or embossed sections of 95 the counter relatively high enough for perfect work.

If desired, a chisel-edged tool 9 may be substituted for doing the work performed by the fine punch 6 as above described, although the latter is preferable because of its ability to round corners and sharp curves, and to fit into small spaces.

The counter, overlay or underlay having 100 been thus prepared, its plate 3 is slid into the ways 2 of the press table 1, a sheet of paper or cloth secured over it, and the printing or embossing proceeded with in the usual manner.

I prefer to have the shanks 11 of the tools 110

made tapering and a square shoulder 12 provided therefor in order to facilitate the ready exchange of the tools.

By this method of preparing the counter, 5 overlay or underlay, not only is considerable time saved in comparison with the use of a knife, but the work is performed more uniformly and perfectly and with less danger of injury to the counter by any accidental slipping of the knife.

What I claim as my invention is:

1. The process of preparing a counter, overlay or underlay, which consists in providing the exposed surface of a layer of 15 yielding material with an impression of the matter to be printed or embossed, punching lines of closely disposed holes to a predetermined depth adjacent the printing or embossing, and then lowering the surface of 20 said layer outside said lines.

2. The process of preparing a counter, overlay or underlay, which consists in pasting a sheet of cardboard upon a layer of yielding material, providing the exposed 25 surface of the cardboard with an impression of the matter to be printed or embossed, severing the cardboard adjacent the printed or embossed matter, and then tearing away the sections of cardboard separated 30 from the printed or embossed matter.

3. The process consisting in providing the

exposed surface of a layer of yielding material with an impression of matter to be printed or embossed, punching lines of closely disposed holes adjacent said matter, and 35 then removing to a suitable depth the sections of said material outside said lines of holes.

4. The process of preparing a counter, 40 overlay or underlay, which consists in providing the exposed surface of a layer of yielding material with an impression of matter to be printed, cutting lines of closely disposed holes to a predetermined depth adjacent said printed matter, lowering the surface of the yielding layer outside of but near to said lines, and then compressing restricted areas in quick succession outside of 45 said lowered sections of the yielding layer.

5. The process consisting in providing the exposed surface of yielding material with an impression of the matter to be printed or embossed, punching lines of closely disposed holes into said material adjacent said matter, tearing away the sections of said 55 material outside said lines, and then compressing restricted areas in sections of the yielding material outside said lines.

In testimony that I claim the foregoing invention, I have hereunto set my hand this 25th day of January, 1924.

CLARENCE R. SMITH.
